United States Patent Office

Des. 198,401
Patented June 9, 1964

198,401

PHONOGRAPH

Richard W. Lanigan, Arlington Heights, Ill., assignor to
Sawyers, Inc., Portland, Oreg., a corporation of Oregon

Filed Jan. 8, 1964, Ser. No. 78,121

Term of patent 14 years

(Cl. D56—4)

FIG. 1

TIG-5

TIG-4

FIG. 1 is a perspective view showing the front, top and one side of a phonograph embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and

FIG. 7 is a left side elevational view thereof.

I claim:

The ornamental design for a phonograph, substantially as shown.
